UNITED STATES PATENT OFFICE.

CHARLES J. VAN DEPOELE, OF CHICAGO, ILLINOIS.

INDUCTORIUM.

SPECIFICATION forming part of Letters Patent No. 298,431, dated May 13, 1884.

Application filed December 31, 1883. (No model.)

To all whom it may concern:

Be it known that I, CHARLES J. VAN DEPOELE, a citizen of the United States, residing at Chicago, in the county of Cook and State 5 of Illinois, have invented certain new and useful Improvements in Inductoriums or Current-Generators, of which the following is a specification, reference being had therein to the accompanying drawings.

10 My invention relates to new and useful improvements made in electrical generators such as patented by me May 16, 1882, No. 257,990, for which application was filed April 8, 1881, and said improvements consist in the construction 15 and winding of such machines, as herein fully described, reference being had to the annexed drawings, forming part of this specification.

Figure 1 shows a front view of the machine 20 complete and ready for operation. Fig. 2 shows a plan view of the armature and the field-magnet poles, the brushes, and commutator. Figs. 3 and 4 are diagrams of circuit combinations of the machine. Fig. 5 shows a 25 vertical cut through the center of machine, the circuits of the same, and also the current-regulator R.

In the present drawings similar letters indicate similar parts.

30 A represents the armature. a and a' are independent armature-coils. B is the field-magnet, provided with polar extensions N and S. C and C' represent the helices of said field-magnet. D is the iron base supporting the 35 machine. E and E' are commutators independent of each other. E is connected to the coils a a, &c., and E' is similarly connected to the coils a' a', &c., of the armature A. F' F² F³ F⁴ are brushes bearing upon the commutators E and E'. h h h are brush-holders for the brushes F' F² F³ F⁴. c c and e e are copper conductors giving passage to the current to the inner and outer circuits of the machine. H is a cross-bar carrying the brush-holders 45 h h h. I is the shaft carrying the armature A. J is a bearing in which the shaft I is kept in place, and wherein it revolves. N and S are the north and south poles of the field-magnet B, between which the armature revolves. p', 50 p², p³, and p⁴ are the binding-posts to the machine. p and n are the leads to the lamps.

Having described the different parts of the machine or generator, I will now proceed to explain the same while in operation.

This machine is especially designed to operate incandescent lights with currents of high tension, or such as are used to run arc lamps, and enables me to place a number of such generators or inductoriums in circuit with arc lights. The current which is furnished in 55 such circuit is used to rotate the armature of the inductorium, and said armature, as above stated, being wound with two independent sets of coils, one set is used to produce the motion between the poles of its field-magnet, 60 while the other set is used to produce a current of lower tension with which to run incandescent lamps. I have found that in operating incandescent lamps in conjunction with arc lights the results are not at all satisfactory 65 as regards the steadiness of the lights, due to the constant variation of the resistance in the main or arc-lamp circuit, caused by the consumption of the carbons. So, in order to secure a steady current for the incandescent 70 lamps, instead of using the direct current, I use the induced current produced in the set of armature-coils not in common with the primary set, which primary coils are directly in circuit with the arc lamps. The induced current is perfectly steady, while the primary or 75 main current may be fluctuating. To change the magnetic condition of a body of iron takes an appreciable time; hence the armature and field-magnet in this machine, which are under 80 the influence of a fluctuating current, cannot vary their magnetism as fast as the fluctuations in the main current, which are instantaneous, so that the induced current set up in the coils intended for the incandescent lamps 85 is not at all affected by the fluctuations of the main current, while variations of longer duration will be more perceptible, but will be gradual enough to allow for regulation of the variations which would take place, thus keeping 90 the induced current steady at all times. Further, in order to make the inductorium more perfect, I have modified the circuits in the same so as to automatically regulate the current to the work.

As shown in Fig. 3, the primary or inducing current passes through the armature-coils a a,

entering at F^3 and leaving at F^4 . This will cause the armature to revolve between the poles of the field-magnet B with a speed commensurate with the amount of current flowing through said coils a , a' , &c. At the same time a current will be induced in the coils a' , a'' , &c., and collected by the brushes F^1 and F^2 . As shown in Figs. 4 and 5, the field-magnet B is wound with two sets of coils, C and C' , each of which is connected with a separate armature, one field-magnet operating both. Part of said current is sent through the field-coils C and C' and the main portion to the lamps $l l l$, &c. Thus the more lamps are switched in (to a certain point) the higher the degree of magnetism will be in the armature, and the stronger the current around the field-magnet, thus more and more opposing the motion of the armature, when a corresponding increase of current will be allowed to pass through the primary or armature coils a , a' , so as to automatically adjust the current produced to the work in circuit.

Fig. 4 shows another diagram of circuits around the armature and field-magnet cores. In this case the primary or the inducing current enters at F^3 . The main portion passes through the armature-coils a , a' , &c., while a smaller portion passes through the field-magnet coils C and C' , which are in a derivation from the coils a and a' , the current leaving at F^4 . The induced current produced in the coils a' , a'' , &c., is collected by the brushes F^1 and F^2 , and from F^1 sent through the field-coils C and C' before reaching the lamp-circuit. By conductor p the current passes in multiple arc through the lamps $l l l$, &c., and by conductor n returns to brush F^4 , thus completing the circuit. It will be readily understood now that before any current is taken from the induced coils, under the action of the inducing-current, the armature and its coils, reacting upon the poles of the field-magnet B, would rotate with a constantly-increasing speed far above that which the machine is calculated to run. So, in order to avoid this, a suitable speed-governor can be attached to the spindle of the armature and be arranged to work a current-regulator, diverting so much of the main current to the main circuit as is not used by the inductorium. An arrangement similar to that shown and described in Letters Patent No. 291,650, granted to me January 8, 1884, would answer the present purpose. The moment some incandescent lamps are placed in circuit an induced current will flow in the coils of the armature set apart for this, and this current, being in opposite direction to the inducing-current, will have a tendency to magnetize the armature-core in opposite direction from the main or inducing current, thus causing a reduction in speed of the armature. This opposing force of the induced current will depend upon the amount of current used outside of the machine. Thus, to compensate for this, a proportionate amount of current will be sent

through the inducing-helices of the armature and field-magnet, thus keeping up the induced current to its normal strength. The mode adopted by me is shown in Fig. 5. Still other combinations of circuits in the inductorium can be used—as, for instance, the main current can be passed through the inducing-coils of the armature and have the field-coils in a derivation from the armature, while the induced current can be collected directly from the armature without passing the current through the field-helices; but this is not so effective; or the inducing-current can be made to flow through a derivation from the armature around the fields, and a similar derivation can be taken from the induced helices and sent around the field-magnet, as shown in Fig. 5.

Instead of winding the inducing and induced coils side by side on one armature-core, two or more independent cores can be used and each wound with helices or coils, as may be required. One armature is set apart to run the others. The driving-armature may have its field-magnets in a derivation from the armature, or be connected in series with the same, while the armatures set apart for the induced current may excite their own field-magnets; or any other combination may be made, provided at all events that part of the induced current reacts upon the inducing field-magnets. As seen in Fig. 5, two armatures are mounted on one shaft. One receives the current from a source of electricity, and drives itself and at the same time the second armature, which latter gives an induced current to the incandescent lamps $l l l$, &c. As shown in Fig. 5, the current from the main line or source enters at P^3 , and by brush F^3 passes to armature A' through coils a' , and by brush F^4 passes out to main conductor P^1 . The coils C on the field-magnet B constitute a separate exciting-circuit therefor, and are in a derivation from the main line, being energized directly therefrom through conductors c , c' . To the conductors P^3 and P^1 , respectively, are connected suitable wires, o' and o . o is in contact with the bar b , while o' is in contact with the lower ends of the resistances r , r' , &c. The upper terminals of the resistances come out in contact with the contact-springs i , i' , &c. Thus it will be seen that if the bar b were pressed down upon the contacts i , i' , &c., nearly all of the current would be diverted from the inducing-coils to the main line. In order to operate the contact-bar automatically, it is at one end provided with an iron core or plunger actuated by the solenoid m , which is connected between the two poles of the lamp-circuit p and n . The induced current in armature A is collected by the brushes F^1 and F^2 , and by posts p' and p'' is led to the lamps $l l l$, &c., by conductors p and n . Part of the current in this circuit is also sent around the field-magnet B, the coils C constituting a second set, and being in a derivation from the second

armature, A, through conductors $c' c'$. The solenoid m is of high resistance, and, as seen, connected in parallel circuit with the lamps $l l l$, &c. Thus, as soon as the machine is started by the establishment of a proper current through the inducing-armature and field-coils, a current will be generated in A, so that in case of only a few lamps in circuit, as soon as more current is present in the lamp-circuit than is safe, the solenoid m will correspondingly draw in its core and lower the bar b upon the contacts $i i i$, &c., thus diverting part of the current from the inducing-coils to the main line or source. By properly adjusting the action of the bar b upon the contacts $i i i$, &c., any number of lights can be used up to full capacity, and at any time will retain their constancy and brilliancy.

What I claim as new, and desire to secure by Letters Patent, is—

- 20 1. An inductorium or current-generator consisting of an armature and field-magnet provided with coils through which a proper current can be made to circulate, in order to produce the rotation of said armature, in combination with armature-coils wound upon the same core as the driving-armature coils, or wound upon independent armature-cores, but driven by the first, between the poles of a common field-magnet, the coils of which are in a derivation from the primary armature, substantially as and for the purpose described.
- 25 2. In an inductorium or current-generator, an armature driven by a current furnished in an arc-light circuit or other source of electricity, in combination with armature-coils wound upon one or more cores, mounted upon a shaft between the opposite poles of a field-magnet, a derivation from said secondary circuit being also wound upon said field-magnet, and connections whereby the rotation of the system will induce current in a portion thereof, said induced current being utilized partly to run incandescent lamps or do other work, and partly to intensify and steady the magnetic field, and thereby to prevent the varia-

tions of the arc circuit affecting the induced current, as described.

3. An inductorium or current-generator having an armature and field-magnet provided with coils through which a proper current is made to circulate, so as to produce a rotary motion of said armature between its field-magnet poles, in combination with an armature or armatures driven by the first armature, in order to produce an induced current in the driven armatures, and proper connections by means of which a small portion of the induced current is diverted through the coils of the field-magnet common to the driving and driven armatures, the main part of the induced current being utilized outside of the machine to run incandescent lamps or to do other work, as may be desired.

4. In an inductorium or current-generator, a driving and a driven armature running between the poles of a field-magnet common to both armatures, the driving-armature and its field-magnets receiving the current from an arc-light circuit or other source of electricity, while the current generated in the driven armature is divided between the outside work and a set of independent coils around the common field-magnet in order to steady the induced current.

5. The combination, with an inductorium or tension-reducing device, as above described, of an arc-light circuit furnishing current to drive the armature or armatures in said inductorium, and a regulator forming a derivation from the main circuit, but controlled by the current of the secondary circuit, and arranged to short-circuit the field-magnets to a greater or less degree, according to the requirements of the said secondary circuit, substantially as described.

In testimony whereof I affix my signature in presence of two witnesses.

CHARLES J. VAN DEPOELE.
